MACHINES FOR POLISHING OR OTHERWISE TREATING HEADED ARTICLES.

Joseph Alexander Cleiff, Walsall, England, assignor to Aluminium Bronze Company Limited, Walsall, England.

Application July 20, 1954, Serial No. 444,586

Claims priority, application Great Britain July 21, 1953

11 Claims. (Cl. 51—108)

This invention has reference to machines for treating wood screws and like headed articles, and is particularly concerned with machines for polishing the heads of such articles.

The principal object of the invention is to enable the heads of wood screws or like articles to be treated automatically without having to be handled at any stage between the time a batch of articles is tipped into the machine and the time the whole of the batch has been subjected to the treatment.

A further object of the invention is to enable a maximum number of articles to be subjected to the treatment in any given unit of time.

Amongst the other objects of the invention are to control the number of articles subjected to the treatment in a given unit of time so that the machine cannot become overloaded or choked, to control the travel of the articles through the machine so that there is no tendency for them to pile up on top of one another at any stage during their travel, to enable the machine to be modified in a simple, efficient and speedy manner so that it is capable of treating articles of different sizes, within reasonable limits, and to ensure that articles of non-standard dimensions and/or shape are sorted and rejected prior to the actual treatment.

In order that the invention may be more readily understood and carried into practice, reference will now be made to the accompanying drawings wherein:

Figures 1, 2 and 3 are respectively, a side elevation, front elevation and plan of a polishing machine, and Figures 4-11 are views illustrating certain details of construction of the machine.

The machine shown in the drawings comprises a base or frame 1 upon which and at the treatment zone of the machine, a turntable 2 is mounted for rotation about the axis of a vertical shaft 3 journaled in the same frame. A band guide wheel 4, located in the same horizontal plane and having the same diameter as the turntable 2, is mounted for rotation about the axis of a vertical shaft 5 which is also journaled in the frame. The top of the turntable 2 is provided with a peripheral lip 6 which is formed with a system of radial slots 7, and an endless band 8, located below the said slotted lip extends around the two turntables, and a jockey pulley 9.

The jockey pulley is mounted for rotation about a vertical spindle 10 projecting upwardly from a slide 11 which is so carried upon the frame that it is adapted for displacement in a path at right angles to the plane containing the shafts 3 and 5, under the control of a tension spring 12, to maintain the endless band at a constant tension.

Identical pinions 13 are made fast upon the lower ends of the shafts 3 and 5, the teeth of the said pinions being engaged by an endless chain 14 which (see Figure 8) also engages the teeth of a driven pinion 15 and of a jockey pinion 16 which latter is journaled upon a spring-loaded pivoted arm 17 to maintain the chain in tension.

The pinion 15 is fast with a vertical drive-output shaft

2

15a which is journaled in the frame 1 and extends downwardly from a gear box 18 through which box the said shaft is driven by a motor 19 carried on the underside of the frame and driving a power input shaft 19a (see Figures 1, 3 and 6) through pulleys 20, 21 and an endless band 22.

One end of an arm 23 is rotatably mounted upon the said power input shaft between the pulley 21 and the gear box; also a second pulley 24 is made fast to the said shaft 10 between the arm and the pulley 21. A shaft 25 is journaled in and transversely of the other end of the arm, a pulley 26 being made fast with one end, and a mop 27 or equivalent polishing device being made fast with the opposite end, of the said shaft.

15 An endless band 28 extends around the pulleys 24 and 26 to impart drive from the input shaft to the mop, and the latter is located above the slotted peripheral lip of the turntable 2 (see Figures 2, 3, 7 and 11).

The mop-supporting arm 23 seats upon a pillar 29 (see Figure 6) which projects upwardly from, but is prevented from rotation in, the frame 1; the lower end of the pillar is screw-threaded and has a bevel gear 30 screwed thereon; the pillar passes freely through, but is held against rotation within horizontal bars 29a and 29b which are fixed in the frame of the machine and between which the bevel gear 30 is supported; the said bevel gear meshes with a second bevel gear 31 which is fast upon a horizontal shaft 32 journaled in and extending to the front of the frame where it is provided with a manually operable wheel 33. Thus, by rotation of the wheel 33, the pillar is adapted to be raised or lowered within the frame to take the periphery of the mop out of or into contact with the upper face of the slotted lip of the turntable 2.

35 A second and horizontal output shaft 34 extending from the gear box, has a radial arm 35 fast therewith, the said arm being connected by a link 36 to a piston 37 which is accommodated within a vertical cylinder 38. The cylinder is mounted upon the said gear box, carries

40 a hopper 39 at its upper end, and the stroke imparted to the piston by rotation of the shaft 34 and arm 35, is sufficient to traverse the piston head between one extreme position below the bottom of the hopper and an opposite extreme position above the top of the hopper.

45 The hopper is adapted to be charged with a batch of screws or similar articles of which the heads are to be polished, and the end face 37a of the piston head is concave or otherwise formed so that, as the piston is driven through its upward working stroke, the piston head is pushed through the articles contained in the hopper and one or more of the articles are collected upon the piston head and are prevented from falling back into the hopper.

55 A third and vertical output shaft 39 (see Figure 2) extends upwardly from the gear box 18 laterally of and parallel to the cylinder 38, the said shaft having a cam 40 fast upon its upper end; the said cam is incorporated in mechanism for transferring each article or group of articles raised by the piston, from the end face of the said piston to the receiving end of a chute whereby the said articles are fed to the slotted rim of the drum 2.

60 The said transfer mechanism includes a blade 41 which (see Figure 3) is pivoted, intermediate its ends, upon a vertical pin 42 fixed upon a bridge 42a spanning the hopper; the said blade is loaded by a spring 43. One end of the blade abuts the periphery of the cam 40 and its opposite end extends over the mouth of the hopper to a position vertically above the piston; the said opposite end of the blade has a depending flange 44 which is adapted to brush over the face 37a as the piston reaches the limit of its working stroke, to remove from the said

3

face any article which may have been raised from the hopper by the piston.

The chute consists of three separate channel-like inclined and superimposed components 45, 46, 47, each having a slot 48 formed in and along its base. The uppermost component 45 extends downwardly and rearwardly from the mouth of the hopper, its lower end being located vertically above but spaced from the upper end of the lowermost component 47 which is inclined downwardly and forwardly towards the turntable 2.

As shown in Figures 4 and 5, the upper end of the intermediate component 46 is connected to the uppermost component at a distance from the lower end of the latter, whereas, its lower end opens to the interior of the lowermost component at any desired position between the ends of the said lowermost component. To ensure that any article which overshoots the intermediate chute component, is fed to the lowermost component, a screen 49 (see Figure 1), having converging sides, is secured to and between the upper end of the lowermost component and the lower end of the uppermost component, so that it is adapted to collect any such article and to transfer the said article to the upper end of the lowermost chute component.

The chute assembly is connected to, and is partially carried by, a magnetic vibrator 50 of any known and suitable construction; the operation of the said vibrator tends to shake all the articles fed into the chute to the base of one or other of the chute components so that the shanks of the said articles project into and downwardly of the slots in the bases of the components, where they are supported by their heads and are caused to traverse the complete assembly in succession.

The slots 48 in the chute components are arranged in a common vertical plane so that when one article enters and is suspended within a slot in either of the two upper components, it is fed from that slot into the slot of a lower component. On the other hand, should an article, whether of standard dimensions or otherwise, fail to enter the slot in the uppermost component, it travels relatively rapidly down and beyond the lower end of the said component, is collected by the screen 49 and transferred to the lowermost component; if such article still fails to enter the slot in the lowermost component, again it passes relatively rapidly down and beyond the lower end of the latter and is rejected.

To enable such rejected articles (which, at least to a large extent, will consist of articles of non-standard dimensions) to be collected, a tray 51 is so disposed below the lower end of the lowermost chute component that it is adapted to receive all rejected articles; the tray is inclined forwardly and downwardly of the machine and its lower end opens to a discharge aperture 52 in the front of the frame 1; rejected articles passing through the aperture 52 may be collected in a suitable receptacle.

The sides of the lowermost chute component 47 terminate short of the lower end of the said component to enable rejected articles to fall into the tray 51. However, to enable the articles which are suspended in and traversed along the longitudinal slotted base of the component 47, to be fed to the slotted lip 6, the said base extends to and overlaps a transfer plate 53 (see Figures 7 and 9) fixed upon the frame of the machine and interposed between the chute component 47 and the lip 6 of the turntable 2; the said plate is formed with a cranked slot 54 of which the one end registers with the lower end of the slot 48 in the base of the component 47, whereas its opposite end opens at and substantially radially to the periphery of the slotted lip of the turntable. The transfer plate is not connected to the chute and, therefore, is not subjected to vibration; however, as shown in Figure 9, a portion of the plate which is adjacent the lip 6 is inclined at such an angle downwardly towards the said lip that any article entering the slot 54 travels along the latter under the action of gravity.

4

Although it is intended that the articles should be transferred from the hopper 39 to the uppermost chute component 45 at a controlled rate which is determined by the speed at which the piston 37 is reciprocated and by the number of articles which the recessed face of the piston head is capable of supporting during any one working stroke, nevertheless, there is a tendency for the articles to accumulate in the transfer plate 53 and the adjacent end of the base of the chute component 47, more particularly when the leading articles of a fresh batch reach the discharge end of the chute. In the event of such an accumulation taking place, it is possible that, as still more articles are added thereto, the vibration may cause the articles to pile up and jamb within the discharge end of the chute; to prevent such circumstances arising, a resilient tongue 52 (see Figure 1) is secured to and projects from the lower end of one side of the lowermost chute component; when the machine is at rest, the said tongue seats upon the outlet end of the portion of the base of the component 47 which extends beyond the sides of the component; however, when the machine is operating and the chute is being vibrated, the tongue is oscillated violently towards and away from the said projecting base portion so that it imparts a succession of light blows to the heads of any articles accumulated in the discharge end of the slot 48.

The turntable is rotated continuously whilst the machine is in operation and as the leading article travelling along the slot 54 in the transfer plate 53 reaches the turntable lip, it passes into one of the radial slots 7 in the lip as the mouth of the said slot passes the outlet end of the plate slot, and thereafter is carried away by the turntable 2.

The radial slots are of a depth such that only one article can be accommodated in any one slot at the same time and to ensure that the article is retained within the slot with its head seated firmly on the upper surface of the lip before that portion of the article which depends below the said lip is gripped between the band and turntable periphery, a fixed arcuate shield 55 (see Figure 7) is arranged adjacent to the lip edge between the transfer plate and the zone of the turntable periphery where the band comes into contact with the said periphery; a flexible blade 56 which seats upon the upper face of the lip, is provided on the said shield. Further on the opposite side of the transfer plate to the shield, there is provided a resilient blade 57 which is anchored by one end to a vertical post 57a fixed upon the machine frame; the said blade extends towards the zone of the turntable periphery where the band 8 leaves the latter, the free end of the said blade making rubbing contact with the turntable periphery and its anchored end being spaced radially outwards of the edge of the lip.

Hence, after the grip on the depending portion of each lip-supported article is released, the said portion rides on to and along the resilient blade 57 and is constrained to move away from the turntable periphery with the result that the article is removed from the slot and falls below the turntable. One end of the blade 57 rubs against the body of the turntable 2 below the slotted lip thereof, the opposite end of the blade being anchored at post 57a (see Fig. 7). As the articles are so removed, they are collected in a second discharge tray 58 disposed below the turntable 2 and extending downwardly and forwardly of the machine, the lower end of the tray opening to an aperture 59 in the front of the machine, through which aperture the articles are discharged into a suitable receptacle.

The polishing mop or equivalent device 27 is located between the zones where the band 8 comes into contact with and leaves the turntable periphery.

To ensure that each article or group of articles raised by the head of the piston 37 is transferred in its entirety to the upper end of the uppermost chute component 45, an open-ended funnel 60 is secured to the said component end; the large open end of the funnel overhangs the mouth of the hopper 39 whereas its opposite and smaller end

opens into the chute between the sides of the component 45. A depending and rearwardly inclined ledge 61 is provided on the upper edge of the smaller funnel end to minimise the possibility of the articles, as they are transferred to the funnel from the piston face by the blade flange 44, being thrown clear of the chute.

Push button switches 62 for starting and stopping the motor 19 and vibrator 50 are mounted on the front of the machine.

To operate the machine, a batch of wood-screws or like headed articles is charged into the hopper 39 and the motor and vibrator are started. The motor drives the input shaft 19a to the gear box 18; the said shaft rotates the mop 27 and the drive from the shaft is transmitted through the gear box to the three output shafts 15a, 34 and 39. Consequently, both the turntable 2 and the band guide wheel 4 are rotated, the piston 37 is reciprocated, and the cam 40 is rotated, continuously.

The rotation of the cam 40 forces the blade 41 to swing about its pivot 42 in the direction which tensions the spring 43 and moves the flange 44 away from the funnel 60 to the side of the piston opposite the said funnel. Therefore, as the nose of the cam rides beyond the blade, the latter is spring-driven rapidly in the reverse direction, the said spring-driven movement being timed to take place as the piston reaches the end of its upward or working stroke.

Hence, the flange 44 impels any article or articles which has or have been lifted from the hopper upon the piston head face, from the said face into and through the funnel and then into and down the vibrating uppermost chute component 45. The shanks of the said articles enter the slot 48 and the articles are suspended by their heads in the said slot so that they travel in succession down the chute component 45; each article is transferred by the component 46, or the screen 49, to the lowermost component 47, eventually being discharged from the projecting end of the base of the said lowermost component, along the slot 54 in the transfer plate, into a slot 7 in the peripheral lip 6 (see Figure 9). The rotation of the turntable 2 therefore carries the articles in succession away from the transfer plate, each article again being suspended by its head within a slot 6 so that its head is located on top of the lip and its shank extends downwardly alongside the periphery of the turntable. Initially, each article is retained within its slot and its head is pressed upon the top of the lip, by the shield 55 and resilient flange 56 respectively; hence the upper face of the head is located horizontally and is prevented from damaging the periphery of the mop when brought into contact with the latter. As the article passes beyond the flange 56, its shank is gripped (see Figure 11) between the band 8 and the turntable periphery.

Since both the turntables 2 and 4 are of uniform diameter and are rotated by the chain 14 and shafts 3, 5, the band 8 is driven by frictional contact with the turntable peripheries so that the said band does not tend to disturb the position of the gripped article relatively to the turntable or to displace the upper face of the article head from its horizontal position.

Before the leading article is fed into the slotted lip 6, the wheel 33 is turned by hand so as to lower the arm 23 and to bring the periphery of the rotating mop 27 into close proximity to the upper face of the turntable. Consequently, as each article is carried around in the said lip, the upper face of its head is polished by the mop, as indicated in Figure 11.

Finally, the polished article passes the zone where the band 8 leaves the turntable periphery and comes into contact with and rides along the external surface of the blade 57 (see Figure 10) so that it is removed positively from its slot in the lip 6 and falls into the tray 58 down which it travels to and through the aperture 59.

Should an article, due to its size or for any other reason,

fail to enter and traverse the slot 48 of the chute, it travels rapidly down each of the components 45, 46 and 47 and, upon reaching the ends of the sides of the component 47 falls from the latter into the rejection tray 51 and through the aperture 52.

To enable the machine to be adjusted for polishing a batch of articles of any given size, the slot 48 in the chutes 45, 46, 47 is variable in width. Thus, the component 45 comprises two longitudinal parts which are held in spaced relationship by telescopic straps 62 of which one is shown in Figure 4, the intermediate component 46 also consisting of two longitudinal parts each of which is secured to, and is therefore adjustable simultaneously with, the corresponding parts of the component 45. The lowermost chute component again comprises two longitudinal parts of which the lower edges of the bases are interconnected by hinges 63 (see Figure 1) and the hinge pins consist of bolts to which nuts are applied to enable the parts of each of the hinges to be secured against relative movement.

Instead of forming a concave end face on the piston head, an upstanding rim or rib may be provided around the said head. Further and to vary the number of articles transferred to the chute over any given period, or to enable the same number of articles of different standard dimensions to be transferred in the same period, the head may be detachably assembled to the body of the piston so that, as and when desired, it may be replaced by a head having a face of a different area.

Whilst the invention has been specifically described with reference to a polishing machine, it should be understood that certain of its components, for example the mechanism for transferring the articles from the hopper to the chute assembly, and the chute assembly itself, are capable of being incorporated in machines suitable for other purposes; wherein batches of relatively small, headed articles are to be transferred from the hopper to the treatment zone of the machine.

What I claim is:

1. A machine for treating the heads of screws and like headed articles, comprising a hopper for storing a batch of the articles to be treated, a turntable disposed at a lower level than the hopper and having a peripheral lip which is formed with a number of radial slots opening outwardly of the turntable, a longitudinally slotted feed chute extending downwardly between the hopper and the peripheral lip, a tensioned band extending around a part of the turntable periphery located below the said lip and spaced circumferentially of the turntable from the chute end against the lip, power driven means for rotating the turntable and means for transferring the articles in succession from the hopper to the chute.

2. A machine for treating the heads of screws and like headed articles, comprising a hopper for storing a batch of the articles to be treated, a turntable located at a lower level than the hopper and having a peripheral lip which is formed with a number of radial slots opening outwardly of the turntable, a longitudinally slotted chute extending downwardly between the hopper and the peripheral lip, a tensioned band extending around a part of the turntable periphery located below the said lip and spaced circumferentially from the chute end adjacent the lip, power driven means for rotating the turntable and imparting turntable driven endwise movement to the band, a resilient arcuate shield contacting the turntable periphery below the said lip and between the said chute end and the position where the said band feeds on to the turntable, the said shield being provided with a resilient arcuate flange which overhangs and contacts the upper surface of the lip, an article treating tool located above the said lip and the band-contacted part of the turntable, and means for transferring the articles in succession from the hopper to the chute.

3. A machine for treating the heads of screws and like headed articles, comprising a hopper for storing a batch

of the articles to be treated, a turntable located at a lower level than the hopper and having a peripheral lip which is formed with a number of radial slots opening outwardly of the turntable, a longitudinally slotted chute extending downwardly between the hopper and the peripheral lip, a tensioned band extending around a part of the turntable periphery located below the said lip and spaced circumferentially from the chute end adjacent the lip, power driven means for rotating the turntable and imparting drum-driven endwise movement to the band, a resilient arcuate shield contacting the turntable periphery below the said lip and between the said chute end and the position where the said band feeds on to the turntable, the said shield being provided with a resilient arcuate flange which overhangs and contacts the upper surface of the lip, a resilient blade disposed between the said chute end and the position where the band leaves the turntable, one end of the said band being anchored in spaced relationship to the turntable periphery and its opposite end making contact with the said periphery between the said anchored end and the said position where the band leaves the turntable, an article treating tool located above the said lip and the band-contacted part of the turntable, and means for transferring the articles in succession from the hopper to the chute.

4. A machine for treating the heads of screws and like headed articles, comprising a hopper for storing a batch of articles to be treated, a turntable disposed at a lower level than the hopper and having a number of radial slots opening to its periphery, a wheel of the same diameter and located in the same plane as the turntable, a jockey pulley journalled on a slide located in the said plane, between the turntable and wheel, the slide being loaded by a spring urging it away from the turntable and wheel, an endless band extending around the turntable, wheel and pulley, power driven means for rotating the turntable and wheel at identical speeds, and imparting endwise movement to the band, a longitudinally slotted feed chute extending downwardly from the hopper to that part of the turntable periphery which is not contacted by the band, means for transferring the articles in succession from the hopper to the chute, and an article treating tool disposed adjacent that part of the turntable periphery which is contacted by the band.

5. A machine for treating the heads of screws and like headed articles, comprising a hopper for storing a batch of the articles to be treated, a turntable located underneath the said hopper and having a number of radial slots opening to its periphery, a chute extending downwardly from the hopper to the turntable periphery and comprising three longitudinally slotted components, namely an upper component which extends downwardly and away from the chute, a lower component which extends downwardly to the turntable periphery, and an intermediate component extending between the ends of the said upper and lower components remote from the hopper and turntable respectively and the said components being located in the same vertical plane, power driven means for rotating the turntable, means for transferring the articles in succession from the hopper to the said upper chute component, and an article treating tool disposed above the slotted turntable periphery at a position removed from the end of the lower chute component which is adjacent the said periphery.

6. A machine for treating the heads of screws and like headed articles, comprising a hopper for storing a batch of articles to be treated, a turntable disposed at a lower level than the hopper and having a number of radial slots opening to its periphery, a longitudinally slotted feed chute extending downwardly from the hopper to the periphery of the turntable, a gear box, a drive input shaft to the gearbox, an arm journalled about the shaft and carrying a rotatable article-treating tool above the slotted periphery of the turntable and means for transmitting drive from the shaft to the tool, a first drive

output shaft from the gear box and means for transmitting drive from the said output shaft to the turntable, mechanism for transferring articles in succession from the hopper to the shaft, second and third drive output shafts from the gear box, and means for transmitting drive from the said second and third shafts to said transfer mechanism.

10. A machine according to claim 6 wherein the mechanism for transferring the articles from the hopper to the chute comprises a piston which is slidably accommodated within a cylinder disposed below and opening into the hopper, a crank fast with the said second output shaft and linked to the piston for reciprocating same within the cylinder and the hopper so as to raise the piston head at least to the level of the top of the hopper, a spring loaded blade journaled upwardly of the latter and extending towards the piston, a drive transmitting shaft geared to the said third output shaft and having a cam fast thereon, the said cam being arranged in abutment with the blade for turning the latter against spring action and releasing same to permit spring actuation of the blade transversely of the head of the piston when the latter is at the upper end of its stroke.

25. A machine according to claim 6 wherein a pinion is fixed upon the first output shaft, the turntable is fast upon a driven shaft on which a second pinion is fixed and an endless chain engages said pinions for transmitting drive from the said output shaft to said driven shaft.

30. A machine according to claim 6 comprising a wheel of the same diameter as and located in the plane of the turntable, a tensioned endless band passing around the peripheries of the turntable and wheel, a pinion fixed to the said first output shaft, the turntable being fast upon a first driven shaft on which a second pinion is fixed, the wheel being fast upon a second driven shaft on which a third pinion is fixed, the said second and third pinions being of the same diameter, and an endless chain passing around all three pinions for transmitting drive from the said first output shaft to the said driven shafts, turntable and wheel and from the turntable and wheel to the endless band.

35. A machine according to claim 6 comprising a wheel of the same diameter as and located in the plane of the turntable, a tensioned endless band passing around the peripheries of the turntable and wheel, a pinion fixed to the said first output shaft, an arm journalled about the axis of the said output shaft and having a jockey pinion journalled thereon, the turntable being fast upon a first driven shaft on which a second pinion is fixed, the wheel being fast upon a second driven shaft on which a third pinion is fixed, the said second and third pinions being of the same diameter, an endless chain passing around the said three pinions and the jockey pinion and the arm whereon the said jockey pinion is journalled being loaded by a spring which acts on the arm to tension the chain.

40. A machine according to claim 6 comprising a wheel of the same diameter as and located in the plane of the turntable, a tensioned endless band passing around the peripheries of the turntable and wheel, a pinion fixed to the said first output shaft, an arm journalled about the axis of the said output shaft and having a jockey pinion journalled thereon, the turntable being fast upon a first driven shaft on which a second pinion is fixed, the wheel being fast upon a second driven shaft on which a third pinion is fixed, the said second and third pinions being of the same diameter, an endless chain passing around the said three pinions and the jockey pinion and the arm whereon the said jockey pinion is journalled being loaded by a spring which acts on the arm to tension the chain.

45. A machine for treating the heads of screws and like headed articles, comprising a hopper for storing a batch of articles to be treated, a turntable disposed at a lower level than the hopper and having a number of radial slots opening to its periphery, an upper longitudinally slotted chute component extending downwardly away from the said chute, a lower longitudinally slotted chute component disposed vertically below the said upper component and extending from that end of the said upper component which is remote from the chute downwardly to the vicinity of the slotted periphery of the turntable, an intermediate longitudinally slotted chute component fixed to the said remote end of the upper component and extending into the said lower component, a screen fixed to the said remote end of the upper component and to the corresponding end of the lower component, a vibrating device operatively connected to one of said components for vibrating the complete chute, and a transfer plate which spans the distance between the lower end

of the said lower component and the periphery of the turntable, the said plate being overlapped by the said lower end and having a slot therein which registers with the slot in the said lower component and extends to the slotted periphery of the turntable, power driven 5 means for rotating the turntable, means for transferring the articles in succession from the hopper to the adjacent end of the upper chute component, and an article treating tool disposed above and adjacent the slotted turntable periphery.
